UNITED STATES PATENT OFFICE.

MILTON ADOLPHUS DALTON, OF CINCINNATI, OHIO.

PERMUTATION-LOCK.

SPECIFICATION forming part of Letters Patent No. 329,820, dated November 3, 1885.

Application filed August 17, 1885. Serial No. 174,605. (No model.)

To all whom it may concern:

Be it known that I, MILTON ADOLPHUS DALTON, a citizen of the United States, residing at Cincinnati, in the county of Hamilton and State of Ohio, have invented certain new and useful Unlockers which produce Improvements in Permutation-Locks; and I do hereby declare the following to be a full, clear, and exact description of the invention, such as will enable others skilled in the art to which it appertains to make and use the same.

The superior safety of keyless combination or permutation locks is everywhere acknowledged; but occasionally persons are met with who object to these locks because they are difficult to unlock, saying that not only must the secret formula of the combination be remembered, but to work it out by the aid of a dial in the way heretofore known requires a steady hand, as well as light in some form, and eyesight—requisites which are not always at command. It is well known that these keyless combination-locks are unlocked by turning the lock-arbor in accordance with a secret rule or formula, turning alternately in reverse directions and halting each time at a different number on the dial. Nervous or old people find it difficult to unlock even a simple combination-lock, let alone a complex fine bank-lock, the unlocking formula of which contains perhaps no less than six numbers, so that the lock-arbor has to be turned to and stopped at six different numbers on the dial, in predetermined order, during as many as twenty right and left turns.

The object of my invention is to provide facilities whereby the turns and halts of the lock-arbor, in working out the combination, or, in other words, unlocking such a combination-lock, are controlled mechanically; and to this end it consists of an unlocker so organized with a combination-key and a governor that one or the other of these parts may engage the external end of the lock-arbor to turn it, subject to deadlocks between such key and governor, which deadlocks occur successively, turning right and left alternately, and stop the arbor mechanically at each predetermined halt of the combination. By means of such an unlocker the particular combination-lock to which it is adapted may

be unlocked in the dark by the sense of feeling alone, and by any person soever, provided the key has been set to the proper combination.

My invention can be embodied in a variety of forms.

In order that it may be clearly understood, I have illustrated in the annexed drawings, and will proceed to describe, several forms 60 thereof.

Form 1.—Figure 1 represents an axial section of the unlocker, showing it as applied to a lock-arbor, the section being taken in the plane indicated by broken line *x x* of Fig. 2. 65 Fig. 2 represents a front view of the unlocker. Fig. 3 illustrates a series of permutable bits for the combination-key. Fig. 4 represents a front view of the governor. Fig. 5 represents an axial section of the governor, 70 taken in the plane indicated by broken line *y y* of Fig. 4. Fig. 6 illustrates the split ring for covering the dial. Fig. 7 is a diagram of the respective circles described by the key-bits and by the governor-pins, also 75 showing by radial lines the arcs of motion successively imparted to the two pin-barrels of the governor by each turn of the key. Figs. 8, 9, and 10 illustrate one modification, and Figs. 11, 12, and 13 another modification, of 80 one of the governor's pin-barrels to adapt the unlocker for working out twice as long a combination.

This unlocker is adapted for unlocking combination-locks of the character described 85 in my United States Patents No. 221,789 and No. 221,790, in which locks the combination is worked out by alternate lifts of the so-called "controller," and settings of the so-called "permutter," the unlocker illustrated in the 90 first seven figures, which I will describe first, being adapted to a lock requiring three settings of the permutter to four lifts of the controller in working out the combination.

The combination-key consists of a disk, A, 95 and permutable bits B B' B² B³. The edge of the disk A is provided with a continuous series of closely-contiguous and equidistant slits, *a*, and around the inner circle of these slits the disk has a circular recess for a dial-face 100 by which the slits are suitably numbered. A split guard-ring, D, is placed in the dial-re-

cess, exposing but a fraction of the dial. This split guard-ring is circularly movable, so that it may expose any desired part of the dial. The permutable bits are stiff flat strips of metal fitting edgewise in the slits *a*, and having forked tails to clasp the disk beyond the slits, and at the same time hold the split guard-ring in place. The active part of each bit is a small tooth (marked, respectively, *b*, *b'*, *b''*, *b'''*) projecting beyond the outer edge of the main body of the strip. The position of the tooth on any one bit differs from the position of that on every other bit, so that when the bits are attached to the disk *A* their teeth lie in different planes, as illustrated in Fig. 3. The disk *A* is suitably constructed to concentrically engage the exterior end of the lock-arbor *C*, and has a knob by which it may be conveniently turned after it has been applied to the lock-arbor.

The governor consists of two pin-barrels, *E* and *F*, of equal diameter, mounted side by side on studs *e* and *f*, projecting from a bed-plate, *F'*, which may be permanently attached to the door. These pin-barrels are geared together by like spur-wheels, *E'* and *F'*, so that motion given to either imparts an equal motion to the other. Pin-barrel *E* is but a disk circumferentially studded with three equidistant pairs of radial pins, 1 and 1^a , 2 and 2^a , 3 and 3^a , all the pins being set in the same cross-plane and having the same length. The distance between the two pins of each pair from center to center is equal to an arc of thirty degrees. Pin-barrel *F* is also provided with three circumferentially-equidistant pairs of similarly-spaced radial pins, 4 and 4^a , 5 and 5^a , 6 and 6^a . The two pins of a pair are located in the same cross-plane on this barrel; but the plane of each pair differs from that of every other pair, as well as from that of the pins of barrel *E*, so that the twelve pins of these two pin-barrels are disposed in four different planes coinciding, respectively, with the four planes of the teeth of the four key-bits *B*, *B'*, *B''*, *B'''* when the combination-key is applied to the lock-arbor. In this example the tooth of bit *B* then lies in the plane of the three pairs of pins of barrel *E*, the tooth of bit *B'* in that of pins 4 and 4^a , the tooth of bit *B''* in that of pins 6 and 6^a and the tooth of bit *B'''* in that of pins 5 and 5^a . The pin-barrels occupy such positions with reference to the axis of the lock-arbor (which forms the axis of rotation of the combination-key when applied) that the key-bits can engage the pins *seriatim*, as will be presently explained more fully. A pawl, *G*, is applied to spur-wheel *E'* to prevent the pin-barrels from being turned in working out the combination of the lock, except each in the direction indicated by the respective arrows in Fig. 2, so that the combination-key must be turned from left to right to transmit motion by its bit *B*, but from right to left to transmit motion by either one of its other three bits to the pin-barrels. The pin-barrels are so intergeared and receive such impulses from the successive driving actions of

the key-bits that, supposing a pin to stand on a line drawn from the center of the combination-key or lock-arbor to the center of pin-barrel *E*, the remaining pins will, by the required successive right and left turns of the combination-key, be successively turned into position to be driven by successive key-bits, a pair of pins of one barrel succeeding a pair of pins of the other barrel in regular order, because each pin is successively acted upon and driven through an arc of thirty degrees by the appropriate key-bit. The parts are here so proportioned that when the second pin of a pair of either barrel has been driven forward as far as the appropriate key-bit can drive it, then the first pin of a pair of the other barrel will coincide with a line drawn from the center of this other barrel to the center of the combination-key. The number of teeth in the wheels *E'* and *F'* is also a multiple of the whole number of pins in the two pin-barrels, so that the pawl *G* may properly fall behind a tooth at the end of each impulse given to the pin-barrels.

Observing that the lifts of the controller of my lock before mentioned are, in this instance, assumed to require the turning of the lock-arbor from left to right and the settings of the permuter turn from right to left, also that the lifts and settings require two turns and a fraction of a turn each, and, finally, that the lifts are all completed at the same point in the third turn, while each setting requires stoppage at a different point, I will explain how to obtain the combination for the key required for working out the combination of the lock.

Apply disk *A* without any key-bits and without the split guard-ring to the lock-arbor. Then turn the pin-barrels by hand until pin 1 coincides with a line drawn from the center of the lock-arbor to the center of barrel *E* and throw pawl *G* into gear. Then turn the lock-arbor by disk *A* from left to right, and stop when you see, by observation of the lock, that you have given a full lift to the controller. Now see what slit *a* in disk *A* is opposite pin 1, and take the number of this slit, turn disk *A* back a little and put key-bit *B* in said slit. Now turn from right to left two turns, causing key-bit *B* to successively drive pins 1 and 1^a before it, so that pin-barrel *F* will be turned until its pin 4 coincides with a line drawn from the center of disk *A* to the center of the said barrel. Continuing to turn a little farther in the same direction, observe the lock, and stop turning when you see that one of the permuter-pins is under the controller-pin. Now take the number of the slit *a* which is opposite pin 4, and turn the disk back a little to place key-bit *B'* in said slit. Then turn again from left to right, whereby key-bit *B'* will be caused to successively drive before it pins 4 and 4^a , so that pin 2 of barrel *E* will be moved to the position occupied at the start by pin 1 thereof. Continuing to turn from left to right a little farther, key-bit *B* will strike pin 2, and

since by that motion pin-barrel E cannot be turned, being prevented by pawl G, the key is brought to a dead stop, and at the precise point where the lift of the controller is completed the 5 second time. Turn again from right to left, and find the position for and apply key-bit B², as was done with respect to key-bit B'. Then turn again from left to right to make another lift, as before, and finally turn once more from 10 right to left to find the position for key-bit B³. The numbers marking the slits for the different key-bits must be duly impressed on the memory. The combination-key may then be removed, the key-bits withdrawn, and the 15 split guard-ring put in the dial-recess of the disk. The key-bits may be applied to the disk A at any time, the dial and the split in the guard-ring affording the means of finding the proper slits for the respective bits.

20 The guard-ring is useful in hiding the numbers of the combination of the key-bits, so that the unlocker may be used in the presence of lookers-on without danger of giving any sufficiently accurate clew to the relative positions 25 of the key-bits, to obtain which by observation merely is made still more difficult by the similarity of the key-bits as to all points, except the position of the driving-teeth.

In working out the combination of the lock 30 with the key thus prepared, it is essential that at the start pin 1 stand on a line drawn from the center of the key to the center of barrel E. That this position of pin-barrel E may be attained by the sense of feeling, I provide pawl G with a reverse pawl, G', adapted to engage a notch, e', in barrel E, when said barrel assumes the particular position mentioned.

To unlock, proceed as follows: After applying the key, turn the arbor to the starting-point, the same as is done in the ordinary operation of unlocking my aforesaid locks. Next turn pawl G to disengage wheel E' and let reverse pawl G' bear on pin-barrel E. Then 45 turn the pin-barrels by hand in directions reverse to the arrows of Fig. 2 until reverse pawl G' drops into the notch e' of pin-barrel E and stops further rotation of the pin-barrels. Disengaging the reverse pawl and throwing pawl 50 G in gear with wheel E' completes the preliminary work. Now turn the key from left to right until bit B strikes pin 1, arresting motion in that direction. This completes the first lift. Then turn from right to left until stopped 55 by bit B' striking pin 4. This effects the first setting of the permuter. Proceed in this way, turning alternately in reverse directions to a dead stop each time, until finally, on reversing after the last lift, the bolt of the lock is without 60 drawn.

Fig. 3 shows a series of seven key-bits, by the use of which, together with a suitably constructed and operating pin-barrel, F, a lock requiring seven lifts of the controller and six 65 settings of the permuter may be unlocked. When in such case it is desirable or preferred to maintain the relative proportions of the

parts as before described, the pin-barrel F may consist of a sleeve so mounted on a tubular neck of gear-wheel F' that said barrel can be adjusted along said neck. Thus in the lowest position on such neck the pins of barrel F would be in range, respectively, of the key-bits B', B², and B³, while in its highest position the pins would be in range of the key-bits B⁴, B⁵, and B⁶. Figs. 70 75 8, 9, and 10 illustrate one way of constructing such a pin-barrel F. It is held in either position on the neck by an inwardly-projecting pin, f', on the barrel entering one end or the other of a devious slot, f², cut in the said neck, 80 so that the barrel cannot turn thereon, a spring, f³, being placed in a cavity in the barrel, which causes its pin to be pressed up into the locking ends of said slot. The barrel is adjusted by first forcing it along the neck to 85 unlock its pin, after which the barrel is turned and slid along the neck, and then turned back again to let its pin enter the other end of the slot.

Another form of adjustable barrel F is 90 shown in Figs. 11, 12, and 13. In this case inwardly-projecting pins of the barrel engage straight longitudinal slots in the neck, and the barrel is adjusted along the neck and held in position by means of a nut, f⁴, on stud 95 f, and a spring, f⁵, placed in the tubular neck, the nut and spring acting antagonistically on the inwardly-projecting pins of the barrel. This adjustable pin-barrel is held in one position until the third setting of the permuter 100 and the fourth lift of the controller have been effected, then the barrel is shifted so as to bring its pairs or pins respectively in range with the alternate key-bits B⁴, B⁵, and B⁶, when the operation of unlocking is resumed and 105 finished. It is important to prevent the pin-barrels from turning while barrel F is being shifted. I therefore apply a pawl, H, to gear-wheel F', as shown in Figs. 1 and 2, which can be thrown in gear, and in conjunction with pawl 110 G prevent any turning of the barrels.

To adapt this unlocker to combination-locks which require a variable number of turns, right and left alternately, of the lock arbor—as, for instance, four turns right, then three 115 turns left, then two turns right, &c.—as is the case with many combination-locks, it is only necessary to use pin-barrels having instead of pairs of pins, groups of four, three, &c., and to arrange every group of the two barrels in a different cross-plane, so that a separate key-bit 120 is required for each group.

Form 2.—Fig. 14 represents a perspective view of this form of unlocker. Fig. 15 represents an axial section thereof. Figs. 16, 17, 125 18, 19, and 20 illustrate various parts of the unlocker in detail. The unlocker shown in these figures is adapted to any one of my aforesaid locks requiring four lifts of the controller and three settings of the permuter to 130 work out the combination of the lock.

The combination-key consists of a central cylindrical stem, I, (so constructed that it may concentrically engage the lock-arbor,) and a

series of four permutable key-bits, (marked, respectively, $I^1 I^2 I^3 I^4$, and strung on the stem, together with intervening washers, $i^1 i^2 i^3$.) A cross-bar, I^5 , screwed on the outer end of the stem and locked by a set-screw, serves the purpose of clamping the key-bits so as to hold them firmly in the relative positions in which they may be arranged, and also forms a handle for turning the key. A washer, i^4 , is placed between the cross-bar and the bit I^4 .

The governor consists of a fixed hollow cylinder, K , a tubular longitudinally-split pin-barrel, K' , fitted in said cylinder, a solid pin-barrel, K^2 , fitted in barrel K' , and a spring, K^3 , placed under barrel K^2 , and tending to project it. Cylinder K is fixed on a plate, I^6 , which may be permanently attached to the safe-door, and which may also form the base for a removable dial used in ascertaining the combination of the lock and setting the permutable key-bits accordingly. Near its base cylinder K has a segmental cross-slot, k . Above this slot k it has a longitudinal slot, k^* , obstructed by projecting baffles $k' k^2 k^3 k^4 k^5$, and provided with segmental cross-slots $k^6 k^7$, k^8 , as best shown in Fig. 18. Pin-barrel K' has a pair of pins, 7 and 7^a , which project through the slot k of cylinder K , so that they may be struck successively by key-bit I^1 to turn barrel K' . Pin-barrel K^2 has a single pin, 8, which projects through the longitudinal slot of pin-barrel K' , and also through the slotted side of cylinder K , protruding so far from the latter that in certain positions it will be in range of one or another of the key-bits I^2 , I^3 , and I^4 . Pin-barrel K^2 projects from pin-barrel K' as well as from cylinder K , and its outer end is provided with a suitable knob for operating it by hand. Key-bit I^1 terminates 40 with a yielding tooth, i , in the form of a pin, the head of which lies in a longitudinal cavity in the body of the bit against a spring which keeps the tooth projected. This yielding tooth is provided in order that in turning the lock-arbor from left to right, as is required preparatory to starting the unlocking operation, this key-bit I^1 may be forced past pin 7 when pin 7^a has reached the end of slot k , as shown in Fig. 14. However, this conjunction of the parts will be at once conveyed to the operator by the sense of feeling, because the spring-tooth offers considerable resistance to such forced passage, and it is essential that the operator should know, because in working out the combination of the lock a lift of the controller is completed at each such conjunction. The plane of cross-slot k^6 corresponds with the plane of key-bit I^2 , the plane of cross-slot k^7 with that of key-bit I^3 , and the plane of cross-slot k^8 with that of key-bit I^4 . Key-bits I^1 , I^2 , and I^4 are plain unyielding strips of metal.

The combination for the key-bits—that is, the required relative arrangement thereof—may be readily ascertained from working out the combination of the lock by mere observance thereof, and noting at the halts, by the aid of a dial or other device, first, what position is re-

quired for the key-bit I^1 to strike pin 7 when said pin is in the position shown in Figs. 14 and 18; secondly, where key-bit I^2 must be placed to strike at the completion of the first setting of the permuter-pin 8, which is then in the end of cross-slot k^6 ; thirdly, the required position of key-bit I^3 to strike at the completion of the second setting of the permuter-pin 8, which is then in the end of the cross-slot k^7 ; and, lastly, the required position of key-bit I^4 to strike at the completion of the third setting of the permuter-pin 8, which is then in the end of cross-slot k^8 .

Any one of my aforesaid locks may be unlocked by this form of the unlocker, the key-bit having been first duly arranged in proper combination. Apply the combination-key to the lock-arbor and turn first three times to the left, and then three times to the right, at the same time holding the knob of pin-barrel K^2 , so that neither pin-barrel can turn, and key-bit I^1 must be forced past pin 7. See that pin 8 is in the lower end of slot k^8 under baffle k' . Now turn the key from left to right and stop when the key-bit I^1 strikes pin 7, (which is still in the position shown in Figs. 14 and 18.) This makes the first lift of the controller. Next turn from right to left. The first turn in that direction causes key-bit I^1 to turn the pin-barrels by pin 7 far enough to turn pin 8 from under baffle k' , so that the spring K^3 will project pin-barrel K^2 until its pin 8 strikes baffle k^2 . The second turn in the same direction causes key-bit I^1 to turn the pin-barrel by pin 7^a far enough to carry pin 8 to the end of cross-slot k^6 . On the third turn in the same direction key-bit I^2 strikes pin 8 and the key is brought to a dead stop. This completes the first setting of the permuter. Turning the key again from left to right, key-bit I^2 will, on the first turn, rotate both pin-barrels by pin 8 so far as to turn pin 7^a to the position shown in Figs. 14 and 18 to be occupied by pin 7, and key-bit I^2 escaping from pin 8 leaves it in position under baffle k^6 . On the second turn to the right, key-bit I^1 turns both pin-barrels by pin 7^a , moving pin 8 from under baffle k^2 , so that spring K^3 will again project pin-barrel K^2 until its pin 8 strikes baffle k^3 . On the third turn to the right, stop when key-bit I^1 strikes pin 7, which makes the second lift of the controller. Turning again to the left, proceed to make the second setting of the permuter. Thus turn alternately to the right and to the left, turning each time until the key is brought to a dead stop, and you will unlock the lock without any effort of the memory or the eye.

Figs. 21, 22, and 23 illustrate modifications in the details of the construction of the key of the unlocker just described. The key-bits are here screwed into loose rings, and have tapering points adapted to press into V -shaped grooves around the stem of the key to fasten onto it by friction, as clearly shown. The key-bits are square bars with a round tooth at the outer end, so that they can be

turned by an ordinary clock-key to unscrew them or to screw them home. The key-bit I', which corresponds to key-bit I', Fig. 15, has a tooth seated against a spring; but the tooth 5 is provided with a laterally-projecting pin, which permits the tooth to yield or locks it rigidly, according as said pin is turned into a longitudinal slot or into a cross-slot in the key-bit. Thus, after the lock-arbor has been 10 turned to the starting position, this tooth can be locked by turning its pin into the cross-slot, so that in the working out of the combination of the lock this key-bit cannot be forced past the governor-pin.

15 Form 3.—Fig. 21* represents an axial section of this form of unlocker. Fig. 22* represents an elevation of the same. Fig. 23* represents a cross-section in the plane indicated by broken line *x x* of Fig. 22*. Fig. 20 24* represents a cross-section in the plane indicated by broken line *y y* of Fig. 22*.

In its general characteristics this unlocker 25 resembles the one designated as "Form 2." The combination-key consists of a central cylindrical stem, T, an unchangeable or fixed key-bit, V², and a series of five permutable key-bits (marked, respectively, *t t' t' t' t'*) strung on the stem together with intervening washers, the said washers being provided each with a 30 tongue to engage a longitudinal groove in the stem T. The permutable key-bits and washers are clamped between the collar of the fixed key-bit and a clamping-nut, T⁴, on the screw-threaded end (which I term the "upper" end 35 for the sake of distinction) of the stem, and above this nut the stem is provided with a fixed milled head for turning it. The lower end of the stem is adapted to enter a socket in the lock-arbor, (not shown,) and is provided with 40 a pin, T⁵, to engage said arbor. The bore of the lower end of the clamping-nut is enlarged to receive a spiral spring, T⁶, which exerts a 45 constant downward pressure on the washers and permutable key-bits, and which, by preventing the too easy turning of the latter when the nut is unscrewed, facilitates arranging them in the desired combination.

The governor consists of a fixed tubular barrel, U, a trundle mounted to turn on said 50 barrel, a check-disk in constant engagement with the upper head of the trundle, and a rider, U', mounted on the bars of the trundle. Barrel U is provided with a base-plate, T⁷, which has a pin, T⁸, to enter a hole in the safe-door, (not shown,) and a ring-extension which 55 encircles the lower end of the stem T of the combination-key, and thus yokes it to the lower end of the governor. The axis of the barrel is parallel to the axis of the key. The 60 upper and lower ends of the barrel are smooth and form fixed journals, on which the respective heads of the trundle turn. The intervening external portion of the barrel has a series of twelve circular grooves, so arranged that 65 the upper groove and the next four alternate grooves lie in the respective planes of the five permutable key-bits, while the two lowest

grooves lie in the plane of the fixed key-bit V². All the grooves and dividing-ribs are intersected by a longitudinal groove, u⁶, which is 70 parallel to the axis of the barrel. A notch, v, is cut across the uppermost dividing-rib to connect the adjacent circular grooves, and a similar notch, v', is cut across every alternate dividing-rib below it, all said notches v being 75 on a line parallel to the axis of the barrel. A similar line of notches, v', is cut across the intervening dividing-ribs; but this line of notches is removed by a number of degrees from the line of notches v, as clearly shown in 80 Fig. 24*. The trundle consists of the lower head, u⁴, the upper head, u⁵, and a series of four connecting-bars, u u' u' u', each of which bars is encircled by a spiral spring, u¹³. The lower head, u⁴, of the trundle is provided with 85 two laterally-projecting pins, V and V', adapted to be struck successively by the fixed key-bit V² on turning the key. The upper head, u⁵, is yoked to the key by a yoke having the form of two connected rings, one of which encircles 90 the lower end of clamping-nut T⁴, while the other encircles the said upper trundle-head. The rider U' is a circular collar slipped on the connecting-bars of the trundle above the spiral springs, and provided with a cross-pin, 95 U², the inner end of which engages the grooved portion of barrel U, while its outer end projects so far that it may be struck by the key-bits. The position of pin U² with reference to pins V and V' on the lower trundle-head may 100 be about that shown in Fig. 24*. The check-disk U³ is supported above the upper end of barrel U, and the upper trundle-head on the upper end of a stem, u¹², which is fitted in the tubular barrel U, and encircled by a spiral 105 spring, u¹¹, within the barrel. Spring u¹¹ presses against the head at the lower end of stem u¹², so as to exert a constant downward pull through the stem on the check-disk. The check-disk has two clutch-pins, u⁷ and u⁸, 110 which hold it in constant engagement with the upper trundle-head, entering holes therein, and a stop-pin, u⁹, which is adapted to enter a sectoral slot, u¹⁰, in the upper end of barrel U.

115 It will be observed that the trundle, rider, and check-disk are constantly interlocked, so that they can only turn in unison, and that their turnings are limited by a stop-pin, u⁹, when the latter projects into sectoral slot u¹⁰. 120 This sectoral slot is so located and of such length that so long as stop-pin u⁹ projects into it rider U' may be turned back and forth, so as to carry its pin U² to the notches v and v', alternately, but cannot be turned far enough 125 to carry its pin to the longitudinal groove u⁶. To effect that, the check-disk must first be retracted to draw its stop-pin out of sectoral slot u¹⁰.

130 This unlocker is adapted to any one of my aforesaid locks requiring six lifts of the controller and five settings of the permutter to work out the combination of the lock, and its operation is as follows:

Assuming that the permutable key-bits are arranged in required combination for a given lock, the unlocker is prepared for action by first retracting the check-disk far enough to draw stop-pin u^9 out of sectoral slot u^{10} , then turning rider U' to carry its pin U^2 to longitudinal groove u^6 of barrel U , then depressing the rider in opposition to the springs u^{13} until its pin U^2 reaches the lowermost circular groove on barrel U , and finally turning the rider again to carry its pin to the notch v in the lowermost dividing-rib, which notch is about on a line drawn from the center of key-stem T to the center of barrel U . During the final turning of the rider, and consequently the trundle and check-disk, the stop-pin of the latter is again brought into line with the sectoral slot u^{10} , and the spring u^{11} immediately pulls the check-disk down, so as to project its stop-pin again into said sectoral slot. On releasing the rider springs u^{13} , will slide it up on the trundle to carry its pin U^2 through the said notch v into the next circular groove of the barrel. The key is then turned from left to right. On the first turn the fixed key-bit strikes pin U^2 , carrying it about half-way to the notch v' in the next dividing-rib. On the second turn in the same direction the fixed key-bit strikes pin V on the lower trundle-head, turning the trundle and rider, so as to carry pin U^2 to said notch v' , on reaching which the springs u^{13} again slide the rider up on the trundle, so as to carry pin U^2 through said notch into the next higher circular groove of the barrel. By this time the check-disk has been turned to carry its stop-pin so far toward the other end of sectoral slot u^{10} that during the third turn in the same direction the key is brought to a dead stop when its fixed bit V^2 has turned pin V' on the lower trundle-head to the position shown in Fig. 24*. This completes the first lift of the controller. The key is then turned from right to left. On the first and second turns the fixed key-bit V^2 successively strikes the pins V' and V of the trundle, turning it so as to carry pin U^2 to the notch v in the next higher dividing-rib, on reaching which notch the springs u^{13} again slide the rider up on the trundle, so as to carry pin U^2 through said notch into the next higher circular groove of the barrel. The pin U^2 thus reaches the same cross-plane in which permutable key-bit t moves. By this time stop-pin u^9 has been turned so far back to the other end of sectoral slot u^{10} that the key is brought to a dead stop when permutable bit t has moved pin U^2 so far, during the third turn of the key in the same direction, that said pin U^2 about coincides with a line drawn from the center of the key to the center of the governor. This completes the first setting of the permuter. The key is then again turned from left to right until again brought to a dead stop, as on the first turning, which completes the second lift of the controller. The second setting of the

permuter is effected on again turning from right to left until permutable key-bit t' is brought to a dead stop by pin U^2 . Turning thus alternately from left to right and from right to left is continued until the last lift of the controller has been accomplished, when, on reversing the motion of the key, the bolt of the lock will be retracted.

I term key-bit V^2 a "fixed" key-bit, because it remains fixed in the same position on stem T as long as the unlocker is used for unlocking one and the same combination-lock, the necessary changes in the unlocker required to be made in changing the combination of the lock being effected by rearrangement of the permutable key-bits only; but the fixed key-bit is also so fastened—by set-screw, for instance, as shown—to stem T that it may be adjusted thereon for primary adjustment to any lock.

Form 4.—Fig. 24 represents a perspective view of this form of unlocker. Fig. 25 represents an axial section of the same. Figs. 26, 27, 28, 29, 30, 31, and 32 illustrate parts thereof in detail.

The combination-key of this unlocker is constructed like that of the unlocker designated as "Form 2," except that the yielding tooth of one of the key-bits is omitted. Four key-bits, $L L' L^2 L^3$, are provided in this instance, all alike, strung with intervening washers, $l l' l^2 l^3$, on the stem of the key, and secured by the knob and a locking set-screw.

The governor consists of four hollow posts, $M M' M^2 M^3$, fixed equidistantly in a circle on a circular base-plate, P , which is provided with means to hold it in proper position on the door when the unlocker is used. When applied, the four hollow posts should stand in a concentric circle around the lock-arbor. Hollow post M has a longitudinal slot, m , with a branch cross-slot, o , and contains a pin-barrel, N , the pin n of which projects through the slotted side of the hollow post. A spring, O , under the spring-barrel tends to project it, and the pin-barrel is provided with a stem projecting through the neck of the hollow post, so that such pin-barrel may be pressed along the post by hand in opposition to the spring. The other posts are similarly slotted, the slots being marked, respectively, $m' o'$, $m^2 o^2$, and $m^3 o^3$; but the cross-slots are in different cross-planes. The plane of cross-slot o corresponds with that of key-bit L , the plane of cross-slot o' with that of bit L' , the plane of cross-slot o^2 with that of bit L^2 , and the plane of cross-slot o^3 with that of bit L^3 . The cross-slots o' , o^2 , and o^3 have a like direction and reverse to that of cross-slot o . This arrangement of the cross-slots is required to adapt the unlocker to my aforesaid combination-locks; but for locks that have a number of rotatable disk-tumblers, the setting of each of which requires halting at a different position, the cross-slots o and o^2 must have one and the same direction and the cross-slots o' and o^3 a reverse direction. The other hollow posts also con-

tain each a pin-barrel, (marked, respectively, $N' n'$, $N^2 n^2$, and $N^3 n^3$) and each a spring, (respectively marked O' , O^2 , and O^3 .)

The base-plate P is provided with an unnumbered dial, the numbers being marked on a removable dial-ring, P' , which is used only in ascertaining the required arrangement of the key-bits and in arranging them accordingly before use of the key, and is then removed, so that it will be impossible for any person looking on at the unlocking of the lock to ascertain the correct relative positions of the key-bits.

To unlock one of my aforesaid locks with this unlocker, proceed as follows: See that all the pin-barrels are projected so that their pins are at the outer ends of the longitudinal slots of the hollow posts, and so out of the range of the key-bits. Then turn the key in the known way for moving the parts of the lock to the proper starting position. Next depress pin-barrel N and turn it to move its pin n into cross-slot o . Then turn the key to the right until stopped by its bit L striking pin n . This makes the first lift of the controller. Next turn to the left two full turns. At the first turn, pin n is struck by bit L and turned out of cross-slot o into longitudinal slot m , and the pin-barrel N projected by the spring O , as before. At the end of the second turn stop to depress pin-barrel N' , and turn it to move its pin n' into cross-slot o' , after which resume turning to the left and continue until stopped by key-bit L' striking pin n' . This makes the first setting of the permuter. Next turn again to the right two full turns, which causes pin n' to be turned out of cross-slot o' into longitudinal slot m' , and the pin-barrel N' to be projected by spring O' , as before. Stop at the end of the second turn to again depress pin-barrel N , and turn it to move its pin n again into cross-slot o , after which resume turning to the right and continue until stopped by key-bit L striking pin n . This makes the second lift of the controller.

The second and third settings of the permuter are made in the same way as the first setting, except that pin-barrel N^2 is used for the second and pin-barrel N^3 for the third setting, and the remaining lifts of the controller are all effected in the same way as the second lift.

Form 5.—This form of unlocker, which is illustrated in perspective in Fig. 33, consists of a combination-key resembling that of the unlocker designated as "Form 1," and a governor resembling that of the unlocker designated as "Form 2;" but in this instance the combination-key is fixed, while the governor revolves, being secured to a handle which is suitably constructed to engage the lock-arbor.

With this explanation the construction and operation of this unlocker can be readily understood from the illustration without further description of the details.

Form 6.—Fig. 34 represents a perspective

view of this unlocker. Fig. 35 represents an axial section thereof.

The combination-key of this unlocker consists of a stem, Q , adapted to engage the lock-arbor and provided with an arm, Q' , and a series of rotatable disk-tumblers, $R R' R^2$, loose on said stem. The arm Q' and the tumblers are provided with drive-pins like the driving-arm and disk-tumblers of a combination-lock, and each tumbler has a notch, (marked, respectively, $r r' r^2$.)

The governor consists of a spring-bolt, S , which may be permanently fixed to the safe-door in such position that when the key is applied the spring-bolt may shoot into the notches of the tumblers, as these notches are successively brought into line with said bolt. The spring-bolt may be constructed in any suitable manner.

This unlocker very much resembles an ordinary disk-tumbler combination-lock, and in use operates like it—that is, the stem has to be turned right and left alternately to align the notches of the tumblers with the spring-bolt. The key having first been set to the combination which will adapt it to work out the combination of the lock, unlocking may be effected as follows: After applying the key to the lock-arbor, turn the key a number of times in the direction in which the lock-arbor must be turned, to the first number of the combination of the lock, holding the spring-bolt back in the meanwhile, so as to prevent it from engaging the notch of tumbler R^2 . Then release the spring-bolt and continue turning in the same direction until stopped by the spring-bolt being automatically projected into notch r^2 of tumbler R^2 . Turn in the reverse direction until tumbler R' is engaged by the spring-bolt. Then reverse again and turn until stopped by the engagement of tumbler R by the spring-bolt.

Each deadlock between the key and the governor of the unlocker makes one number of the combination of the lock.

All forms of the unlocker are so constructed that the combination-key, together with its dial, can be easily removed from and reattached to the safe-door, so that the bits of said key, which should be or may be disarranged after use, can be rearranged at leisure and where ample light can be had. The combination-key, once set properly, can be used by any person to open the lock of the safe in the dark, if necessary.

I have described several forms of my invention to show that great variations may occur in its mechanical embodiment. I could easily multiply examples, but deem the foregoing sufficient for the purpose. I believe that I am the first to produce an unlocker for keyless combination-locks which operates to mechanically control the turns and halts of the lock-arbor in working out the combination of the lock—namely, by coming to a dead stop at each number of the combination. I therefore

claim such an unlocker as broadly as is possible within legal bounds.

I claim as my invention—

1. An unlocker for combination-locks, which consists of a combination-key and a governor, substantially as before set forth, whereby the turns and halts of the lock-arbor, in working out the combination of the lock, are controlled mechanically.
2. In an unlocker of the character described, a combination-key consisting of a stem, one fixed key-bit, and a series of permutable key-bits thereon, and a clamping-nut for holding the permutable key-bits in position, substantially as before set forth.
3. In an unlocker of the character described, a governor, substantially as before set forth, consisting of the following elements, viz: an externally grooved and notched fixed barrel, a trundle mounted to turn on said barrel and having two laterally-projecting pins on one of its heads, a rider mounted upon springs on the bars of the trundle and having a laterally-projecting pin, the inner end of which engages the grooved barrel, and a retractable stop-

disk permanently clutched to one of the heads of the trundle, and having a stop-pin adapted to enter a sectoral slot in the end of said barrel.

4. The combination, substantially as before set forth, with a combination-key the stem of which carries one fixed key-bit and a series of permutable key-bits, of a governor composed, essentially, of an externally grooved and notched barrel, a trundle mounted to turn on said barrel and provided with laterally-projecting pins, a rider mounted upon springs on the trundle and having a laterally-projecting pin, the inner end of which engages the grooved barrel, and a retracted check-disk which is permanently clutched to the trundle, and has a stop-pin adapted to enter a sectoral slot in the end of the said barrel.

In testimony whereof I affix my signature in presence of two witnesses.

MILTON ADOLPHUS DALTON.
